COMBINED PLANTER AND BOOKCASE

John W. Sciortino, 255 W. 96th St., Apt. 1G,
Bloomington, Minn. 55420

Filed Feb. 19, 1970, Ser. No. 21,514

Term of patent 14 years

Int. Cl. D6—01

U.S. Cl. D33—2

FIG. 1

FIG. 2

FIG. 3

FIG. 4

FIG. 1 is a view in perspective as seen from one side, one end and top of a combined planter and bookcase, showing my new design;

FIG. 2 is a view in side elevation thereof, showing the side opposite that shown in FIG. 1;

FIG. 3 is a view in end elevation thereof, showing the end opposite that shown in FIG. 1;

FIG. 4 is a view in top plan thereof. The bottom not shown is devoid of ornamentation.

I claim:

The ornamental design for a combined planter and bookcase, substantially as shown and described.
